UNITED STATES PATENT OFFICE

JOHN FORST, OF NEW YORK, N. Y., ASSIGNOR TO MANHATTAN WICKER CO., OF NEW YORK, N. Y., A CORPORATION OF NEW YORK

DESIGN FOR A COMBINATION SEAT AND BACK REST

Application filed March 13, 1929. Serial No. 30,461. Term of patent 7 years.

To all whom it may concern:

Be it known that JOHN FORST, a citizen of the United States, and resident of New York city, in the county of New York and State of New York, has invented a new, original, and ornamental Design for a Combination Seat and Back Rest, of which the following is a specification, reference being had to the accompanying drawing, forming part thereof, in which—

Fig. 1 is a perspective view of a combination seat and back rest showing my new design, and

Fig. 2 is a side elevational view thereof.

I claim:

The ornamental design for a combination seat and back rest, as shown.

Dated, New York city, March 5, 1929.

JOHN FORST.
